UNITED STATES PATENT OFFICE.

JARVIS B. EDSON, OF ADAMS, MASSACHUSETTS.

DESIGN FOR A HANDLE FOR A BRUSH.

SPECIFICATION forming part of Design No. 14,331, dated October 2, 1883.

Application filed August 11, 1883. Term of patent 7 years.

To all whom it may concern:

Be it known that I, JARVIS B. EDSON, a citizen of the United States, residing at Adams, in the county of Berkshire and State of Massachusetts, have invented or produced a new and original Design for Handles for Brushes, Mirrors, Combs, and other Articles, of which the following is a specification.

This design relates to handles for hand-mirrors, brushes, combs, and other handles; and it consists in constructing the handle oval in cross-section and with spirally-arranged ribs or projections, thus imparting to the handle a novel, handsome, and attractive appearance.

In the drawings, Figure 1 represents a plan view of a handle made in accordance with my design; Fig. 2, a transverse section of the same on line $x x$, and Fig. 3 a longitudinal section on the line $y y$ of Fig. 1.

Referring to the drawings, the number 1 designates the body of the handle, and 2 the spirally-arranged ribs or projections, which extend in a uniform spiral line from the end 3 to the extremity 4 of the handle. The end 3 is where the handle is to be joined or joins the article to be furnished with a handle, such article being, for example, a hand-mirror, a

brush, or a comb. The hand is oval in cross-section, so that a flattened rope-like appearance is imparted to it, and the surfaces of the spiral ribs or projections are convex in cross-section, (see Fig. 3,) while the outer end portion, 4, of the handle is bulbous, so that it is larger than the attaching end 3, and the sides and edges of the handle taper in outline from the outer extremity to the attaching end.

By my design a novel, pleasing, and handsome appearance is imparted to handles for hand-mirrors, brushes, combs, and other articles.

Having thus described my invention, what I claim is—

The design for a handle herein described and shown, said handle being tapered, as set forth, and oval in cross-section, and having a bulbous outer end portion, and formed with the spiral projections or ribs, which are convex in cross-section.

In testimony whereof I have hereunto set my hand in the presence of two subscribing witnesses.

JARVIS B. EDSON.
